(57) CLAIM

The ornamental design for a bottle, as shown and described.

DESCRIPTION

1.-2. Bottle

1.1 : Perspective

1.2 : Front

1.3 : Back

1.4 : Left

1.5 : Right

1.6 : Top

1.7 : Bottom

The parts shown by means of broken lines in the reproductions are not part of the claimed design; the hatchings in the representation represent contours only and do not illustrate an ornamentation or decoration on the surface of the product.
